UNITED STATES PATENT OFFICE

2,242,311

STRETCHER

Daniel D. Lucey, Los Angeles, Calif.

Application August 15, 1939, Serial No. 290,210

4 Claims.

(Cl. 5—82)

My invention relates to and has for an object the provision of an improved stretcher wherein a flexible stretcher sheet and a stretcher frame as separate units are adapted to be quickly, conveniently and effectively attached and detached by reason of zipper fastenings related to the sheet in a particular manner to insure a reliable and secure attachment thereof as well as an easy and efficient use of the stretcher without necessitating bodily lifting the patient.

Another object of my invention is to provide a stretcher of the character described wherein the zipper fastenings are spaced from the margins of the sheet and arranged in such manner as to be protected from foreign matter when the sheet is laid on the ground in preparation for attaching the frame thereto, and for also protecting the zippers when the sheet is folded over and fastened to the frame, said folded over portions of the sheet then covering the zippers to thereby prevent foreign matter from clogging and interfering with operation thereof.

A further object of my invention is to provide a stretcher of the character described wherein the frame is of sectional and foldable construction in order that it may be folded into small compass and readily unfolded into position for use.

Yet another object is to provide a stretcher such as described wherein the folding frame is provided with automatic locking means at the joints for locking the frame against collapse when unfolded and in position of use, said locking means being easily manually releasable when it is desired to fold up the frame.

With the foregoing objects in view, together with such other objects and advantages as may subsequently appear, the invention is carried into effect as illustrated by way of example in the accompanying drawing, in which:

Fig. 1 is a top plan view of a stretcher embodying my invention;

Fig. 2 is a top plan view of the fabric body sheet or cover as it would appear when laid out preparatory to attachment to or after removal from a stretcher frame;

Fig. 3 is a cross section on the line 3—3 of Fig. 1, showing in dotted lines the relation of the margins of the fabric sheet and fastening means to the frame and ground, floor or other surface on which such sheet is spread out preparatory to attachment to or when detached from the frame;

Fig. 4 is an enlarged fragmentary longitudinal section of one of the hinge joints of the foldable frame;

Fig. 5 is a sectional view taken on the line 5—5 of Fig. 4;

Fig. 6 is a sectional view taken on the line 6—6 of Fig. 5;

Fig. 7 is a fragmentary side elevation of the frame as when folded.

One form of stretcher embodying my invention generally comprises a rectangular frame A preferably of tubular construction, a body or patient supporting strip or sheet B of canvas or other suitable material, and zipper and strap fastening devices C and D, respectively located at the longitudinal and transverse marginal portions 10 of the sheet whereby the latter may be quickly and easily attached to and removed from the frame while laid upon the ground, a floor, a bed or other supporting surface from which the patient is to be lifted or onto which the patient is to be placed.

In accordance with my invention the cooperating elements of the two zipper fastenings are spaced inwardly of the longitudinal edges of the strip or sheet B, whereby when such sheet is laid upon a supporting surface such as the ground with said zipper elements uppermost, said elements will be protected from direct or other exposure to the ground and foreign matter which might clog and interfere with proper operation thereof. This arrangement is especially advantageous when it becomes necessary to lay the sheet upon wet or muddy surfaces or sandy or loose ground.

With reference to Figs. 2 and 3 it is seen that when it is desired to use the stretcher of my invention, assuming its component parts, the frame A and strip B are disassembled, the strip is first laid upon the surface from which the patient is to be lifted, as shown in Fig. 2 and also by means of the co-planar full and dotted lines of Fig. 3, or if necessary may be folded and manipulated in accordance with established hospital and medical practice, in preparation for lifting and carrying the patient. When the patient is properly positioned on the sheet the physician or attendant folds the marginal portions of the sheet over the longitudinal members of the frame A from position shown in dotted lines in Fig. 3 to position shown in full lines in said figure, and then aligns the zipper elements so that said zipper devices may be fastened in the usual manner for securing the sheet to the frame. When the strap fastenings D are included in the stretcher assembly, it being noted that these fastenings could be eliminated if desired, due to the secure fastening afforded by the zipper devices extending the full length of the sheet, said strap fastenings may be looped around the ends of the frame and snapped in place by means of the snap fastenings D' thereon.

It is now apparent that the stretcher of my invention may be quickly and easily assembled for use in a much more expeditious and reliable manner than heretofore possible, without necessitating the lifting of the patient, it being possible

to "roll" the patient onto the "stretcher." This is especially beneficial where the patient has suffered broken bones or is injured in such manner that lifting or handling other than by prescribed "rolling" might prove injurious or fatal.

It is important to note that the aforesaid spacing of the zippers provides for the covering thereof when the margins of the sheet are folded over and secured in place on the frame as shown in Fig. 3 in full lines. These folded over or overlying portions of the sheet fully protect the zippers from becoming inoperative due to the "clogging" thereof by foreign matter which would otherwise fall or run into the zipper elements.

It is now apparent that the removal of the patient from the stretcher may be effected with the same dispatch and lack of bodily lifting of the patient as when "rolling" the patient on the stretcher.

The frame A as here shown may be of sectional and foldable form whereby when the stretcher is disassembled it may be folded into small compass. Thus, the frame A may comprise a tubular center section 8, and tubular end sections 9 and 10 connected together by means of hinge joints 11 and 12 arranged so that the end sections 9 and 10 may be folded to lie over and under the center section 8, as shown in Fig. 7.

The hinge joints are so constructed that when the sections are unfolded to a common plane or to align with one another they will automatically become locked against hinge action whereby the frame is prevented from collapse and is thereby ready for immediate use.

Each hinge joint comprises solid inserts 13 and 14 riveted in the tubular elements of the sections and formed with opposed ears 15 at their outer ends. A hinge plate or member 16 lies between and is hinged to said ears by means of hinge pins 17, and is provided with flanges 18 extending laterally for contact with the outer ends of the ears 15, to limit the hinge action to one direction. The hinge plates 15 for the set of hinges 11 may be formed so that they will break upwardly and the plates 15 for the set 12 may be formed and arranged so that the hinges will break downwardly as shown in Fig. 7.

As a means for locking the hinge joints I provide for each joint a sleeve 19 which is slidable into and out of position to telescope and lock the joint, as shown in Figs. 4, 5, 6 and 7. Each sleeve 19 is normally held in locking position by means of a spring 20 mounted in one of tubular frame members and having one end engaged with a slide 21 mounted in a slot 22 and abutting the adjacent end of sleeve 19 as shown in Fig. 4. The other end of the sleeve strikes the rivet 23 which acts as a stop, the rivet 24 being countersunk to permit of free movement of the sleeve relative to the hinge joint.

To fold the frame the sleeves 19 of the joints 11 are first retracted from locking position and the end section 9 then folded over the section 8 following which the sleeves 19 for the joints 12 are retracted the end section 10 is folded over the center section 8 as shown in Fig. 7. It should be noted that the sheet is provided with openings 25 to accommodate the hinge joints.

It is now seen that when the frame sections are aligned during the unfolding or extending of the frame for use, the springs 20 will quickly move the sleeves into locking position and thereby

automatically lock the frame in position for use. With this arrangement the frame may be quickly prepared for use and will become as rigid as a solid frame due to the sleeve locks at the joints thereof.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. A stretcher comprising an elongated frame, an elongated flexible sheet having its longitudinal marginal portions adapted to be folded over opposite portions of said frame so as to lie upon the body of the sheet with their free edges nearer to said sides of the frame than to the longitudinal median line of the sheet, and zipper fastening devices extending substantially the full length of and secured to the sheet at points spaced inwardly of the outer edges of said folded over portions so as to be covered by the latter when fastened together.

2. A stretcher comprising an elongated frame, an elongated flexible sheet having its longitudinal marginal portions adapted to be folded upwardly over opposite sides of the frame when the latter is laid thereon, and rows of fastening devices extending substantially the full length of and secured to said sheet at points spaced inwardly of the outer edges of said marginal portions so that when the rows of devices are brought together they may be fastened to one another to independently detachably secure each of the folded over portions of the sheet to the body of the sheet, said fastening devices being covered by said folded over portions when fastened together as aforesaid.

3. A stretcher comprising a frame, a flexible sheet having side marginal portions adapted to be folded upwardly over opposite sides of the frame when the latter is laid thereon, and rows of fastening devices extending substantially the full length of and secured respectively to said folded over portions of the sheet at points spaced inwardly of the outer edges and to the portions of the sheet lying beneath said folded over portions, so that when the rows of devices are brought together they may be fastened to one another to independently secure the margins of the sheet to the frame, said fastening devices being covered by said marginal portions when fastened together as aforesaid, and other fastening means at the end margins of said sheet adapted for detachably securing the sheet to ends of the frame.

4. A stretcher comprising a substantially rectangular open frame, a flexible substantially rectangular sheet of greater width than said frame, having longitudinal marginal portions adapted to be folded upwardly over sides of the frame, and means for independently detachably securing said folded over margins to said frame including detachable fastening devices secured respectively to said folded over marginal portions and the portions of the sheet lying under said folded over portions so that they will lie under said folded over portions in spaced inwardly relation to the free edges thereof when fastened together.

DANIEL D. LUCEY.
